requiring some mechanical device for safety and reliability, these requirements will be met by the use of a self-contained drive which is reliable, simple, and inexpensive. The present invention is directed to a device which is reliable, simple, and inexpensive, and which is particularly well suited for use in aircraft, and which is capable of being easily and inexpensively manufactured.

UNITED STATES PATENT OFFICE

ENGINE STARTER GEARING

James E. Buxton, Elmira, N. Y., assignor to
Bendix Aviation Corporation, a corporation of
Delaware

Application December 22, 1950, Serial No. 202,224

5 Claims. (Cl. 74—7)

1

The present invention relates to engine starter gearing, and more particularly to that type in which a pinion is automatically traversed into mesh with an engine gear, and demeshing is opposed until the engine is reliably self-operative.

Many approaches have been made to the problem of providing a self-contained "anti-kick-out" drive, most of which rely on various types of centrifugal latches which are responsive to engine speed, or to starting motor speed to permit demesh of the drive pinion from the engine gear.

Such drives in which disengagement is controlled by engine speed have the advantage that demeshing will take place reliably at a predetermined engine speed regardless of whether or not the operator holds the starting circuit closed after the engine fires. It is necessary, however, to design the latch to release at a speed considerably higher than the normal idling speed of the engine, since the engine speed in a false start, that is, one in which the engine fails to continue self-operative, may substantially exceed its idling speed. A high speed setting for a positive type of latch is disadvantageous however, since it tends to make the drive noisy and to cause unnecessary wear. It is desirable, therefore, that the latch means be so constituted that it resists disengagement of the drive responsive to weak explosions of the engine, as when it is cold or flooded with excessive fuel, but will permit immediate disengagement responsive to a vigorous engine explosion even at low rotational speeds.

It is an object of the present invention to provide a novel starter drive of the above type which is simple in construction and quiet in operation.

It is another object to provide such a device in which the pinion and its associated parts are permitted to overrun freely when the engine fires, but the driving connection is resumed promptly and without shock in case the engine does not remain self operative.

It is a further object to provide such a device in which the pinion is held in mesh with the engine gear by a detent which is withdrawn by centrifugal force when the rotary speed of the pinion exceeds a predetermined minimum.

It is another object to provide such a device in which the detent is arranged to yield in response to torque caused by a vigorous explosion of the engine even though the rotational speed is insufficient by itself to cause disengagement of the detent.

Further objects and advantages will be ap-

2

parent from the following description taken in connection with the accompanying drawing, in which:

Fig. 1 is a side elevation partly broken away and in section of a preferred embodiment of the invention showing the parts in idle position;

Fig. 2 is a similar view showing the parts in the positions assumed when the engine fires and causes the pinion to overrun the drive; and

Fig. 3 is a view similar to Fig. 1 of a second embodiment of the invention.

In Fig. 1 of the drawing there is illustrated a power shaft 1, which may be the extended armature shaft of a starting motor, on which a sleeve 2 is rigidly mounted as by means of a cross pin 3. The sleeve 2 is formed for a portion of its length with a non-circular cross-section such as a "double D" section, and an angular plate 4 is slidably mounted thereon, being retained by a split lock ring 5.

Sleeve 2 has a reduced cylindrical extension 6 on which a driving clutch member 7 is slidably and rotatably mounted, the longitudinal travel thereof being limited on the one hand by the shoulder 8 formed by a reduction in diameter of the sleeve, and on the other hand by a lock ring 9 seated in a groove formed in the sleeve and accommodated by a counterbore 11 in the clutch member. A driven anchor plate 12 is non-rotatably mounted on the clutch member 7 against a shoulder 13 thereon, and a torsion drive spring 14 has its out-turned ends 15, 16 engaging in radial slots in the anchor plates 4 and 12 so as to yieldably connect the driving clutch member 7 to the sleeve 2 and power shaft 1.

A screw shaft 17 is slidably journaled on the reduced portion 6 of sleeve 2, and is provided with overrunning clutch teeth 18 cooperating with the teeth 19 of driving clutch member 7. Means for limiting the movement of screw shaft 17 away from the driving clutch member is provided in the form of a stop ring 20 anchored on the end of the sleeve 2 by means of a lock wire 21. A spring member 22, and washer 23 are located between the stop ring 20 and the end of the screw shaft.

A pinion 24 is slidably journaled on the power shaft 1 for movement into and out of mesh with an engine gear 25. Means for actuating the pinion is provided comprising a control nut 26 threaded on the screw shaft 17 having radial lugs 27 entering slots 28 in a barrel member 29 and retained by a lock ring 30, the barrel being rigidly connected to the pinion 24 as indicated at 31. The idle position of the control nut is defined by

the ends 32 of the threads of the screw shaft (Fig. 2), while the meshing movement of the control nut is limited by its engagement with the washer 23 of the stop ring 20.

A detent member in the form of a ball 33 is mounted in the control nut 26 and is pressed into engagement with the screw shaft by a spring 34 which bears at its outer end in a cup member 35. This detent is arranged to perform the function of an anti-drift member to yieldingly retain the drive in idle position, and also to resist demeshing of the pinion from the engine gear in case of a false start. The first function is accomplished by means of the formation of an inclined ramp 36 on the screw shaft in position to be engaged by the detent at the start of the meshing movement of the pinion and control nut. The second function is secured by reducing the diameter of the screw shaft adjacent the cranking position of the detent 33, and forming an inclined shoulder 37 over which the detent must be forced in order for the demeshing action to take place. This shoulder 37, as best seen in Fig. 2, is slightly less in height than the radius of the detent 33 so that longitudinal pressure of the control nut caused by a vigorous explosion of the engine will tend to force the detent over the shoulder even though the rotational speed of the parts is at that time insufficient to withdraw the detent from the screw shaft.

In operation, starting with the parts in the positions illustrated in Fig. 1, rotation of the power shaft 1 is transmitted through the sleeve 2, anchor plate 4, spring 14, anchor plate 12 to the driving clutch 7, which is engaged with the end of the screw shaft 17 by reason of the expansion of spring 22. The screw shaft 17 is thus rotated, causing the control nut 26 to move to the right and push the pinion 24 into mesh with the engine gear 25. During this operation the detent 33 passes over the shoulder 36 on the screw shaft, and toward the end of the meshing movement it drops down behind the shoulder 37. When the longitudinal movement of the control nut 26 is arrested by the stop ring 20, the screw shaft 17 is forced to the left compressing the overrunning clutch teeth 18-19 against the resistance of the drive spring 14.

When the engine fires, if the explosion is weak the pinion 24 starts to overrun the power shaft, thus permitting the screw shaft to move to the right, compressing the clutch spring 22 until the overrunning clutch teeth 18-19 are disengaged, thus permitting the pinion, barrel, nut and screw shaft to overrun. At this time further demeshing movement of the pinion is arrested by the engagement of the detent 33 against the shoulder 37 on the screw shaft. If the engine continues to fire and the rotational speed of the pinion reaches a predetermined value, the detent 33 is withdrawn by centrifugal force and the parts permitted to return to idle position. On the other hand, if the initial explosion is a vigorous one, the detent 33 will be immediately forced over the shoulder 37 and demeshing will take place even prior to the attainment of sufficient rotational speed to withdraw the detent by centrifugal force.

If, during the meshing movement of the pinion 24, tooth abutment should occur between the teeth of the pinion and engine gear, the longitudinal pressure so built up will cause the parts which are slidably mounted on the sleeve 2 to move to the left against the pressure of the drive spring 14 until sufficient torque is built up to

cause the pinion 24 to be indexed into proper registry with the tooth spaces of the engine gear, after which the spring 14 will expand and snap the pinion into mesh.

In Fig. 3 of the drawing there is illustrated an embodiment incorporating a separate mesh-enforcing spring for overcoming tooth abutment. As there shown, the lugs 27 of the control nut 26 are longitudinally slidable in the slots 28' in the barrel 29, and a spring 41 is located in the barrel and yieldably presses the control nut 26 against the retaining ring 30 in the barrel. In case of tooth abutment in this embodiment of the invention, the longitudinal pressure caused by arresting the meshing movement of the pinion causes the spring 41 to be compressed by the control nut 26, the lugs 27 thereof sliding in the slots 28' until sufficient torque is built up to index the pinion, whereupon the meshing action proceeds.

In this embodiment, the drive spring 14 is preferably maintained under pressure by the lock ring 9, the counterbore for the lock ring being omitted from the driving clutch member 7 for this purpose. This permits a desirable shortening of the drive, and improves the mesh-enforcing action by the reduction in the inertia of the parts entering into the meshing operation.

Although but two embodiments of the invention have been shown and described, it will be understood that other embodiments are possible, and that changes may be made in the design and arrangement of the parts without departing from the spirit of the invention.

I claim:

1. In an engine starter drive, a power shaft, a sleeve fixed thereon at one end, a driving overrunning clutch member slidably journaled on said sleeve, means including an elastic cushioning member connecting the driving clutch member to the sleeve, thrust means limiting the longitudinal movement of said clutch member away from said cushioning member, a driven clutch member and screw shaft slidably journaled on the sleeve, a stop member on the free end of the sleeve, a compression spring on the sleeve between the screw shaft and stop member, a pinion slidably journaled on the power shaft for movement into and out of mesh with an engine gear, a control nut threaded on the screw shaft, a barrel member connecting the nut and pinion, said screw shaft having a peripheral recess defined at one end by a shoulder, and a yielding detent in the control nut positioned to enter said recess when the pinion is moved into mesh with the engine gear.

2. An engine starter drive as set forth in claim 1 in which the shoulder of the screw shaft and the detent are so formed that acceleration of the control nut with respect to the screw shaft tends to make the shoulder cam the detent out of the recess.

3. An engine starter drive as set forth in claim 1 in which the detent is formed with a substantially spherical engaging surface, the center of which is farther from the axis of the drive than the top of the shoulder on the screw shaft, so as to ride over the shoulder when sufficient force is applied to the control nut in the direction to demesh the pinion.

4. An engine starter drive as set forth in claim 1 in which the screw shaft is formed with a peripheral recess defined by an inclined shoulder in position to receive the detent when the pinion is in idle position.

5. An engine starter drive as set forth in claim 1 in which the control nut is slidably but non-rotatably mounted in the barrel, including further lock means holding the control nut in the barrel and a compression spring in the barrel pressing the control nut against the lock means.
